UNITED STATES PATENT OFFICE.

WILLIAM P. MURPHY, OF SAN JOSE, CALIFORNIA.

DESIGN FOR A SNAP-HOOK.

SPECIFICATION forming part of Design No. 31,003, dated June 13, 1899.

Application filed March 30, 1899. Serial No. 711,167. Term of patent 14 years.

To all whom it may concern:

Be it known that I, WILLIAM P. MURPHY, a citizen of the United States, residing at San José, in the county of Santa Clara and State 5 of California, have invented and produced a new and original Design for Snap-Hooks, of which the following is a specification, reference being had to the accompanying drawings, forming part thereof.

Figure 1 is a side elevation of a snap-hook constructed in conformity with this design. Fig. 2 is a plan view of the same.

This design consists in the shape of the article as shown in the drawings and comprising the wound or spiral shank A, the flattened portion B of the tongue of the snap, and the flattened or rounded portion C of the hook, which form special and distinctive features therein.

The eye D is formed by a continuation of 20 the wrapped wire which forms the shank A, as is the tongue B and the hook-body.

Snap-hooks constructed in conformity with this design are formed from a continuous piece of wire, the flattened portions B and C being 25 pressed and the wire twisted upon itself to form the shank A.

Having thus described the invention, what is claimed is—

The design for a snap-hook substantially as 30 herein shown and described.

In testimony whereof I have hereunto set my hand this 14th day of March, 1899.

WILLIAM P. MURPHY.
